UNITED STATES PATENT OFFICE.

CLARENCE LEWIS COLBERT, OF ELIZABETH, NEW JERSEY, ASSIGNOR TO THE AMERICAN METAL COMPANY, LTD., OF NEW YORK, N. Y., A CORPORATION OF NEW YORK.

METHOD AND APPARATUS FOR AGGLOMERATING MATERIALS.

Application filed May 19, 1922. Serial No. 562,063.

To all whom it may concern:

Be it known that I, CLARENCE LEWIS COLBERT, a citizen of the United States, residing at Elizabeth, in the county of Union, 5 State of New Jersey, have invented certain new and useful Improvements in Methods and Apparatus for Agglomerating Materials; and I do hereby declare the following to be a full, clear, and exact description of 10 the invention, such as will enable others skilled in the art to which it appertains to make and use the same.

This invention relates to the agglomeration of fine ores, concentrates, flue-dust and 15 the like, and particularly to a method and apparatus whereby material of the character described may be converted into a form more readily adapted for handling and subsequent treatment for the recovery of the metallic 20 values therein.

Numerous methods of agglomerating finely divided ore material have been suggested heretofore. Some of them depend upon combustion of the sulphur content of the ore or 25 of added combustible material. The sulphur content of the material is frequently insufficient and, moreover, it is sometimes necessary to preserve the sulphur to ensure proper functioning of subsequent smelting operations. 30 The addition of fuel is costly because combustion in sintering operations is inefficient and wasteful.

To avoid the disadvantages mentioned, it has been proposed to mix an agglutinant 35 such as tar, pitch or the like, or an agglomerating agent such as molten slag with the material. Both of these methods have disadvantages, in addition to the expense involved, of providing lumps or briquettes 40 which crumble readily in the subsequent treatment or which contain a large amount of contaminating mineral impurities.

It has also been proposed to heat the 45 finely divided material by showering it through a flame and thereafter compacting it between rolls and to heat the material in a rotary kiln to a temperature which results in the formation of small lumps which are subsequently compacted into larger lumps 50 by passing through rolls. The former method is impracticable because the time required for passage of the material through the flame cannot be regulated according to the character of the material treated, and 55 consequently the proper heating of the ma-

terial cannot be assured. Furthermore, the furnace chamber will be quickly choked by accumulation of heated particles sticking to the walls thereof. The latter method has been proven impracticable because any attempt to heat the material to a point which will cause formation of small lumps in the rotary furnace results in the formation of rings which adhere to the walls and prevent feeding of the material. These rings can 60 only be removed by stopping and cooling the furnace so that workmen may enter to cut them away. The capacity of the apparatus is limited by the loss of time involved. 65

It is the object of the present invention to 70 avoid all of the difficulties mentioned and to provide a method of and apparatus for agglomerating which is efficient, economical and capable of application to a wide variety of finely divided materials. 75

My invention depends upon the regulation 80 of the temperature and rate of advance of the material under treatment so that substantially no sintering or fritting of the material occurs during the heating thereof. The material is, however, brought to a plastic condition prior to its discharge from the heating chamber. In this plastic condition and while still in substantially its original divided form, the material is subjected to 85 pressure preferably by passing between suitable rolls and is thus compacted into masses suitable for handling and subsequent treatment in metallurgical furnaces and the like. Preferably the heating is conducted in 90 a rotary cylindrical furnace slightly inclined so that the material advances regularly through the heating chamber. The feeding of the material may be varied by changing the rate of rotation to accommodate 95 differences in the sintering points of different materials. Heat is supplied by suitable burners supplied with gaseous, liquid or pulverized solid fuel whereby a flame or 100 flames are projected into the lower end of the furnace. Preferably pulverized coal is used. The products of combustion pass through the heating chamber in the inverse direction to the direction of travel of the material which 105 is thus preheated and gradually brought to the desired temperature as it advances. To ensure proper heating of the material it has been found desirable to provide the kiln with a baffle at its lower end which directs the heated combustion products, generated 110

by the fuel burner, upon the material near the outlet from the kiln. This permits rapid heating of the material in the last stage of its travel to a temperature which renders it 5 plastic and avoids high temperatures in the upper part of the kiln where such temperatures are undesirable. The material which is fed at a rate and subjected only to a temperature which precludes sintering or fritting during its passage through the heating chamber is quickly brought to a plastic condition and is discharged before it becomes 10 agglomerated or has an opportunity to adhere to the wall of the chamber and form 15 rings therein. The plastic material falls from the heating chamber into the compacting apparatus which preferably includes a pair of driven rolls between which the material passes, although other compacting means 20 may be employed.

In order that the invention may be more readily understood, I have shown by way of illustration a suitable apparatus for the practice of the invention in the accompanying drawing, in which—

Fig. 1 is a plan view of the apparatus;

Fig. 2 is a side elevation partially in section thereof;

Fig. 3 is an end view of the apparatus;

30 Figs. 4 and 5 are detail views of one of the rolls; and

Figs. 6 and 7 are detail views of the other roll.

Referring to the drawings, 1 indicates a 35 rotary cylindrical kiln which may be supported and caused to rotate in any suitable manner, the structure and mechanical arrangement of apparatus of this character being well understood in the art. Material 40 may be conveyed to the upper end of the kiln as required. At its lower end the kiln is provided with a stationary combustion chamber 2 in which a burner 3 is mounted. The burner may be supplied with suitable 45 fuel such as pulverized coal, and with air or other combustion supporting agents. A baffle 4 is provided in the combustion chamber to direct the products of combustion downwardly toward the material as it approaches 50 the outlet 5 through which the material is discharged.

The rolls for applying pressure to the material are supported on a frame 6 and surrounded by a shell or casing 7 which serves 55 to prevent escape of the material except through a restricted outlet 9 at the bottom thereof. A shaft 10 is supported in bearings 11 on the frame and passes through the walls of the casing 8. A roll 12 is mounted on the 60 shaft 10 within the casing. As shown in Figs. 6 and 7, this roll consists of a hub 13, a web 14 and rim 15, the rim being provided with a bearing surface 16 and with spaced 65 projecting walls or peripheral flanges 17. The surface 16 is also provided with alter-

nating projections and depressions 18 and 19 to prevent slippage of the roll on the material as it passes thereover.

A complementary roll 20 is supported on a shaft 21 mounted in bearings 22 at the 70 ends of arms 23 projecting from and secured to a rock shaft 24 which is mounted in bearings 25 on the frame. An arm 26 is secured to the shaft 24 and supports a weight 27 provided with a set screw 28 whereby the 75 weight may be secured in any adjusted position along the length of the arm. This weight forms a counterbalance for the roll 20 and by moving it to one or another position the pressure of the roll 20 downward 80 upon the material passing over the roll 12 may be regulated as desired. As shown in Figs. 4 and 5, the roll 20 comprises a hub 29, web 30 and rim 31, the latter being provided with alternating projections and 85 depressions 32 and 33 adapted to cooperate with the projections and depressions on the roll 12 to insure rotation of the roll 20 and to prevent slippage of the roll upon the material to be compressed.

90 The shaft 10 carries at its end a gear 34 meshing with a pinion 35 which is loosely mounted on a shaft 36 rotating in bearings 37 on the frame 6. A clutch member 35' is splined on the shaft 36 and may be moved 95 lengthwise of the shaft by a shifter arm 38 to cause the clutch member 35' to engage or disengage clutch jaws formed on the pinion 35 and thereby connect or disconnect the pinion to or from the shaft 36. The shaft 36 also carries a sprocket wheel 39 driven by a chain 40 from a sprocket wheel 41 on a power shaft 42 which is mounted in bearings 43 and provided with a pulley or other means for driving it.

100 The material which is heated in the kiln to bring it to a plastic condition is discharged in that condition but still in its divided form into the space between the rolls 12 and 20 and between the flanges 17 105 of the roll 12. The roll 12 is rotated through the gearing above described including the pinion 35 and gear 34 so that the material delivered between the rolls is subjected to pressure. Downward pressure of the roll 20 upon the material is regulated by the counter-weight 27 and is sufficient to compact the material as it passes between the rolls. The cooperating projections on the rolls prevent slippage thereof relatively to the material. Whenever it may be necessary by reason of changes in the rate of discharge of the material from the kiln, the roll 20 may move toward or away from the roll 12 110 to adjust itself to the volume of material delivered. The compacted material is delivered through the outlet 9 from the casing 8.

115 Obviously the temperatures and the rate at which the material is fed through the ap- 120

paratus will vary with the characteristics of that material, particularly the temperature at which it becomes plastic and tends to agglomerate by the sticking together of the 5 particles. The necessary regulation to ensure treatment of any given material can of necessity be determined only by trial. When the factors are ascertained, however, materials of the same character can therefore 10 after be treated successfully without difficulty or more careful observation than is usually employed in the operation of similar methods.

My method is characterized and distinguished from all other methods of agglomerating materials by the fact that it is possible thereby to ensure proper regulation and to prevent premature agglomeration and the formation of rings in the heating 20 chamber. The method may, therefore, be operated continuously and without loss of time incident to the removal of such rings. Economical treatment of the material is assured because the heat is applied at its most 25 effective point and, moreover, the waste resulting from radiation in attempting to maintain a considerable zone of the heating chamber at a temperature suitable for agglomeration is greatly reduced. These and 30 other advantages of the method make it highly satisfactory in its practical application to the treatment of finely divided materials.

While the method may be practiced with 35 apparatus other than that illustrated, the apparatus described is well adapted to the accomplishment of the objects noted and is preferred as the best means of commercially utilizing the invention.

40 Various changes may be made in the details of operation and in the apparatus used within the scope of the accompanying claims without departing from the invention or sacrificing any of the advantages thereof.

45 I claim:

1. A method of agglomerating ores, concentrates, flue-dust and like divided material, which comprises causing the material to advance through a heating chamber, subjecting it to gradual heating therein, regulating the rate of travel and the temperature of the material in accordance with its physical characteristics to avoid fusion but so as to discharge it from the chamber in a

55 plastic condition and in substantially its original divided form, and subjecting the divided material to pressure while in the plastic condition.

2. A method of agglomerating ores, concentrates, flue-dust and like divided material, which comprises causing the material to advance through a heating chamber, subjecting it to gradual heating therein to a temperature lower than that at which the material sinters or frits, rapidly increasing 60 the temperature of the material to bring it to a plastic condition without fusion and while retaining substantially its original divided form prior to discharge of the material from the chamber, and subjecting 65 the divided material to pressure while in the plastic condition.

3. A method of agglomerating ores, concentrates, flue-dust and like divided material, which comprises heating the material 75 in an inclined rotary cylindrical heating chamber, regulating the rate of travel of the material so that it is discharged in a plastic condition and in its original divided form with substantially no agglomeration, and 80 subjecting the divided material to pressure while in a plastic condition.

4. In an apparatus for agglomerating ores, concentrates, flue-dust and like material, the combination of a kiln having a 85 discharge outlet, means for supplying combustion products to the kiln at the outlet thereof, and a baffle arranged adjacent the discharge outlet to direct the combustion products upon the material prior to discharge thereof, and means for applying 90 pressure to the material as it is discharged.

5. In an apparatus for agglomerating ores, concentrates, flue-dust and like material, the combination of a rotary cylindrical kiln, a stationary combustion chamber having a discharge outlet at the discharge end of the kiln, means for supplying combustion products to the combustion chamber, a baffle in the combustion chamber 95 adjacent the discharge outlet to direct the combustion products upon the material prior to discharge thereof, and means for applying pressure to the material as it is discharged.

100 In testimony whereof I affix my signature.

CLARENCE LEWIS COLBERT.
